WRINGER HEAD FOR WASHING MACHINES

William B. Beuscher, Kansas City, Mo., assignor, by mesne assignments, to Appliance Engineering Co., Kansas City, Mo., a corporation of Missouri

Application January 16, 1950, Serial No. 138,860

1 Claim. (Cl. 68—255)

1

This invention relates to new and useful improvements in wringer heads for washing machines, and has particular reference to the clutching and indexing mechanisms of said wringer heads.

In washing machines of the ordinary household type, the wringer assembly is disposed over an open-topped tub or tank, being carried by a wringer head. Said wringer head is mounted at the upper end of a vertical power shaft disposed adjacent the side of the tub, and serves to transmit power from said shaft to the wringer rolls, which are usually horizontal. Said wringer head is provided with clutch means whereby the wringer rolls may be started, stopped and reversed. It is also provided with means whereby it may be pivoted about a vertical axis to position the wringer for conveniently transferring the material being laundered from the washing machine tub to other tubs or containers adjacent the washing machine. Customarily the head is provided with indexing means whereby it may be positioned and locked at predetermined intervals in its rotation. Many accidents and injuries have occurred from attempting to turn the wringer head about its vertical axis while the wringer rolls are in operation, and from starting the wringer rolls when the head is intermediate its index positions. In the latter case, the operating torque on the power shaft will tend to spin the head about its vertical axis, with resultant danger to persons standing nearby. The principal object of this invention, therefore, is the provision of a wringer head of the class described wherein the wringer head cannot be rotated about its vertical axis except when the wringer rolls are inoperative, and wherein the clutch cannot be engaged to drive the wringer rolls when the wringer head is moved intermediate its index position.

Another object is the provision of a wringer head of the class described wherein the above described safety device for preventing operation of the wringer rolls is automatically brought into play whenever the wringer head is turned on its vertical axis.

A further object is the provision of a wringer head of the class described wherein the indexing is automatic, requiring no manipulation of levers or the like, and wherein the head is automatically locked against rotation about its vertical axis whenever the wringer rolls are set in operation.

Other objects are simplicity and economy of operation, ease and dependability of operation,

2

and adaptability for use with various types of washing machines.

With these objects in view, as well as other objects which will appear in the course of the specification, reference will be had to the drawing, wherein:

Figure 1 is a fragmentary side elevation of a washing machine including a wringer head embodying the present invention.

10 Figure 2 is a plan view of the parts shown in Fig. 1.

Figure 3 is an enlarged, fragmentary irregular section taken on line III—III of Fig. 2, with parts left in elevation, showing the clutch mechanism 15 in the neutral position.

Figure 4 is a sectional view taken on line IV—IV of Fig. 3.

Figure 5 is a fragmentary section taken on line V—V of Fig. 3.

20 Figure 6 is a fragmentary section taken on line VI—VI of Fig. 3.

Figure 7 is a sectional view taken on line VII—VII of Figure 3.

Figure 8 is a sectional view taken on line 25 VIII—VIII of Fig. 3.

Figure 9 is a sectional view taken on line IX—IX of Fig. 3.

Figure 10 is a fragmentary sectional taken on line X—X of Fig. 3.

30 Figure 11 is a fragmentary view similar to Fig. 3, showing the position assumed by the parts when the wringer head is turned intermediate its index position.

Figure 12 is a sectional view taken on line 35 XII—XII of Figure 3.

Figure 13 is a sectional view taken on line XIII—XIII of Figure 3.

Like reference numerals apply to similar parts throughout the several views, and the numeral 2 40 applies to a washing machine of the ordinary household type including an open topped tub or tank 4 in which is operatively mounted an agitator member 6. A wringer drive shaft 8 extends vertically adjacent the side of tub 4, and is adapted to be rotatively driven by the same power unit, not shown, which operates agitator 6. Said drive shaft is carried in a non-rotating tubular housing 10 which extends above tub 4

45 and about the upper end of shaft 8, and which is rigidly fixed adjacent its upper end in a bracket 12. Said bracket is secured to the outer surface of tub 4 adjacent the upper edge thereof by any suitable means such as rivets 14. A circular index plate 16 is rigidly fixed to housing 50 10 concentrically therewith and in spaced rela-

tion above bracket 12. As best shown in Fig. 9, said index plate is provided with a plurality of notches 18 equally spaced about the periphery thereof. Eight notches are shown, although a larger or smaller number could be used if desired, an even number being preferred. The plate 16 is beveled at the upper rims of said notches, for a purpose hereinafter appearing.

Wringer head 20 is mounted rotatably on the upwardly extended end portion of shaft housing 10. Said wringer head includes a hollow metallic body member 22 having side walls 24 and 26, an outer end wall 28, a top wall 30, intermediate wall 32, and bottom wall 34 extending horizontally between side walls 24 and 26, a cylindrical wall 36 extending downwardly from bottom wall 34, and a cylindrical member 38 disposed concentrically within wall 36 and supported therein by reinforcing webs 40, as best shown in Figs. 7 and 8. Wall 36 normally overhangs and extends slightly below index plate 16, as shown in Fig. 3. All of the above enumerated body member parts are integral, and may be formed by any suitable process, such as die-casting.

Cylindrical member 38 of the body member is axially bored from its lower end to form a socket 42 adapted to fit rotatably over the upper end portion of shaft housing 10, whereby the wringer head may be rotated about its vertical axis and may move longitudinally to said axis. An index pin 44 is rigidly fixed in body member 22 at the lower end thereof intermediate cylindrical walls 36 and 38, being inserted tightly in a tubular support 46 formed integrally with the body member. Said index pin is provided at its lower end with a circular head 48 which is tapered to correspond to the beveled edges of notches 18 of index plate 16. Said index pin is adapted to enter said notches successively by gravity as the wringer head is rotated manually. When said index pin is turned out of one of said notches, it will cam the entire head upwardly until the end surface of said pin rides on the upper surface of index plate 16 intermediate notches 18, as shown in Fig. 11.

Fixed in the wall of shaft housing 10 is a rivet 50 or other suitable stop member, said rivet projecting outwardly from said housing into a groove 52 formed peripherally about the inner surface of socket 42 to limit the upward movement of the wringer head. Said groove is sufficiently wide to permit the index pin 44 to be cammed out of the index plate notches 18 as described, but to prevent any further upward movement of the wringer head. This is accomplished by the abutment of rivet 50 against the lower wall of groove 52, as shown in Fig. 11. The inner wall of socket 42 is provided with a plurality of grooves 54 extending from the lower edge of groove 52 to the lower end of said socket, as best shown in Figs. 7 and 8, said grooves being spaced peripherally about socket 42. Grooves 54 provide that the wringer head may be placed on or removed from shaft housing 10, rivet 50 passing selectively through one of said grooves. It will be noted by a comparison of Figs. 7, 8 and 9 that rivet 50 will be aligned with grooves 54 only at certain indexed positions of the wringer head. When the wringer head is moved intermediate indexing positions, as in Fig. 11, rivet 50 will always be out of alignment with grooves 54, and the wringer head cannot be removed.

A vertical operating shaft 56 is disposed rotatably in body member 22 coaxial with drive shaft 8, being journaled adjacent its upper end in a bearing 58 provided in intermediate wall

and adjacent its lower end in a bearing 60 provided in bottom wall 34. Shaft 56 is prevented from moving upwardly by the close proximity of the upper end thereof to wall 30, and is prevented from moving downwardly by a snap ring 62 disposed in a groove 64 formed in said shaft adjacent the upper surface of body member wall 32. At its lower end shaft 56 extends downwardly into socket 42, and has a transverse slot 66 formed in the lower end thereof for engagement with a tongue 68 formed at the upper end of drive shaft 8. This type of connection between shafts 56 and 8 is axially extensible, permitting the wringer head to be elevated as described above by index pin 44. It also permits easy disassembly of the wringer head from the shaft housing 10.

Carried for free rotation on shaft 56 within body member 22 are a pair of confronting bevel gears 70 and 72. Said gears mesh respectively with diametrically opposite portions of a bevel gear 74. Gear 74 is rotatable about a horizontal axis at right angles to shaft 56, having a hollow tubular hub 76 journaled in a tubular bearing 78 formed integrally with a vertical plate 80. Said plate forms an inner end wall for the body member, and extends vertically between horizontal walls 32 and 34. Said plate seats against a shoulder 82 formed in the body member, and is secured in place by screws 84. Side walls 24 and 26, and walls 32 and 34 of the housing extend past the end of bearing 78 to the right as viewed in Fig. 3, and wringer assembly 86 is secured to walls 32 and 34 by means of bracket 88. Said bracket is provided at its lower end with hooks 90 adapted to project through holes 92 formed in wall 34, and at its upper end is provided with ears 94 adapted to be secured to wall 32 by screws 96.

Wringer assembly 86 includes a pair of horizontally disposed cooperating rolls 98, which are driven through means not shown by a horizontal shaft 100, best shown in Figs. 3 and 4. Said shaft extends outwardly from the wringer assembly into the hub 76 of bevel gear 74, and is transversely slotted at its end to engage a planar bar 102 rigidly fixed in said hub, whereby rotation of gear 74 will rotate shaft 100 to operate the rolls. The top bar 104 of the wringer assembly overlies the top of body member 22, and is provided at its inner end with a depending ear 106 adapted to project downwardly through a hole 108 formed in top wall 30 of the body member. Said ear is provided at its sides with notches 110 for engaging a reduced portion 112 of hole 108, thereby securing said top bar in place.

A clutch member 114 is carried for longitudinal sliding movement on shaft 56 between bevel gears 70 and 72, but is secured against rotation thereon by means of key 116. Said clutch member is provided at each end with longitudinally projecting lugs 118. Corresponding lugs 120 are provided on the inner faces of bevel gears 70 and 72. It will be seen that when the clutch member is disposed centrally between gears 70 and 72, lugs 118 thereof do not engage lugs 120 of either gear. This is the neutral position. When the clutch member is moved upwardly, its lugs engage the lugs of gear 70, thus driving gear 74 and shaft 100 to turn the wringer rolls in one direction. When the clutch member is moved downwardly, its lugs will engage and drive gear 72 to turn gear 74, shaft 100, and the wringer rolls in the opposite direction.

Clutch member 114 may be moved upwardly or downwardly by means of a control shaft 122

coaxial with gear 74 and carried rotatably in a tubular bearing 124 formed integrally with end wall 28 of the body member. At its inner end said shaft carries a flat cam 126 at right angles thereto. A crank pin 128 projects from the inner face of said cam parallel but eccentric to shaft 122. A bearing block 130 carried rotatably on pin 128 is disposed slidably in a peripheral groove 132 formed in clutch member 114. Thus as shaft 122 is turned a quarter turn in either direction from its neutral position, clutch member 114 will be moved upwardly or downwardly to engage gear 70 or gear 72. A hollow handle 134 is secured non-rotatively to the outer end of shaft 22, and serves as a means for manually turning shaft 122. Said handle is provided with a radial extension 136 which serves as an indicator showing the direction in which the laundered material will be passed through the wringer rolls. As shown in Figs. 3, 4 and 5, the rotation of handle 134 is limited by a web 138 formed integrally with body member 22 and projecting into said handle. A pair of webs 140 are formed integrally in the handle and overlap the outer end portion of web 138. Webs 140 are so positioned as to limit the rotation of handle 134 to substantially 90 degrees in either direction from the neutral position.

As best shown in Fig. 6, cam 126, which turns with control shaft 122 is substantially oval in shape, having rounded indentations 142 and 144 formed in the periphery thereof along its minor axis, and rounded indentations 146 and 148 formed in the periphery thereof along its major axis. Said cam comprises a head 150 formed integrally with shaft 122, and a steel sheet metal cup 152 positioned over said head and having the above described indentations therein. Said head has lobes 154 formed thereon for engaging and supporting said cup. It will be noted that the major axis of the cam is horizontal when the clutch member 114 is in its neutral position.

A locking and safety pin 156 is disposed within body member 22 parallel to drive shaft 8 and on the diametrically opposite side thereof from index pin 44. Said pin is carried for axial sliding movement in a bearing 158 formed in bottom wall 34 of the body member, and extends downwardly therefrom through a tubular member 160 formed integrally with said body member. Adjacent its lower end, said pin passes slidably through a washer 162 pressed into the lower end of tubular member 160. A helical spring 164 is disposed about pin 156 within tube 160, bearing at its lower end against washer 162 and at its upper end against a pin 166 inserted transversely through pin 156. Pin 156 is thus urged upwardly at all times. The portion of pin 156 extending above wall 34 passes between a pair of supporting lugs 168 formed integrally with body member 22, and bears at its upper end against the periphery of cam 126, as shown in Fig. 6.

When cam 126 is in its neutral position as shown, the lower end of safety pin 156 projects partially through one of the notches 18 of index plate 16. It is however of smaller diameter than the width of the notch, and will be lifted out of said notch when the wringer head is cammed upwardly by index pin 44. When cam 126 is turned so that its major axis is vertical, to engage the clutch 114, safety pin 156 will project entirely through the index plate, and will lock the wringer head against rotation. When, with the clutch 114 in a neutral position, the wringer

head is turned intermediate its indexing positions, the lower end of safety pin will be closely adjacent the upper surface of index plate 16 intermediate notches 18, as shown in Fig. 11. 5 If it is then attempted to turn handle 134 to set the wringer rolls in operation, the safety pin will be cammed downwardly against the index plate. The reactive force will tend to lift the wringer head, but the wringer head is locked 10 against elevation by the engagement of rivet 50 with the lower wall of groove 52. Thus, handle 134 cannot be turned until the wringer head has been turned to an index position and safety pin 156 is disposed in alignment with one of 15 notches 18 in the index plate. A wringer head which is quite safe in operation is thereby produced. The wringer head cannot be turned from one index position to another except when the wringer rolls are inoperative, and the wringer rolls cannot be set in operation when the wringer head is intermediate index positions. The indexing is automatic in the sense that it requires the operation of no external levers, buttons, or the like, and the safety mechanism functions 20 automatically whenever handle 134 or the wringer head is turned.

It will be noted that in the operation as so far described, only one of the cam indentations on the minor axis of the cam is used, that is 30 the lower indentation 144. The upper indentation 142 is provided to allow for either right or left-hand rotation of drive shaft 8, without disturbing the relation of pointer 136 of handle 134 to the direction of rotation of the wringer rolls, 35 since washing machines are commonly provided with both left and right-hand wringer drives. said pointer should point in the direction in which the laundered material moves between the wringer rolls. The drawing shows the parts positioned for right-hand rotation of the drive shaft. To adapt the device for left-hand drive, handle 134 is removed from shaft 122 and said shaft is turned through 180 degrees, and handle 134 again assembled thereon. This reverses the 40 direction of offset of eccentric crank pin 128, and provides that turning handle 134 in the same direction as before will move clutch member 114 in the opposite direction.

While I have shown and described a specific 50 embodiment of my invention, it is apparent that many minor changes of construction and operation could be made without departing from the spirit of the invention.

What I claim and desire to protect by Letters 55 Patent is:

For use in connection with a wringer assembly having horizontal rolls and adapted to be operated by a rotatably driven vertical drive shaft, a fixed tubular housing coaxial with said drive shaft, a planar index plate secured concentrically to said housing in spaced relation from the upper end thereof, said index plate being notched at spaced intervals around the edge thereof, and a wringer head adapted to carry said wringer assembly, said wringer head comprising a body member having a socket formed in the lower portion thereof which fits for rotary and vertical movement on the upper end portion of said housing, said socket having a recess in the vertical wall thereof, means secured to the housing and extending within the recess for limiting the vertical movement of said body member on said housing, an index pin fixed in said body member and adapted to engage successively the notches 60 in said index plate as said body member is ro-

tated, said index pin being beveled whereby said body member will be elevated to the upper limit of its vertical movement when said index pin is intermediate said notches, a driving connection carried in said body member between said drive shaft and said wringer assembly, a clutch adapted to selectively engage, disengage or reverse said driving connection, a shaft carried rotatably by said body member and adapted when turned to operate said clutch, a cam fixed to said clutch shaft, and a safety pin carried for vertical movement by said body member, resilient means carried by said body member and urging said safety pin against said cam, whereby when said clutch shaft is turned to move said clutch to either of its operative positions, said safety pin will be extended downwardly toward said index plate, the notches in said plate being so positioned that the safety pin can enter one of them only when the index pin is positioned in another of them. 20
